COMBINED RADIO AND RECORD PLAYER CABINET

Alexander Rauchman, New York, N. Y.

Application July 6, 1955, Serial No. 36,829

Term of patent 7 years

(Cl. D56—4)

FIG 2

FIG 1

Des. 176,229

PAGE 2

FIG

3

Fig 4

Fig. 1 is a front elevational view of a combined radio and record player cabinet showing my new design;

Fig. 2 is a side elevational view thereof;

Fig. 3 is a top plan thereof; and

Fig. 4 is a side elevational view thereof with door of record player compartment in open position and radio in operating position.

I claim:

The ornamental design for a combined radio and record player cabinet, as shown.
